UNITED STATES PATENT OFFICE.

ALLAN J. BEATON, OF NEW BRITAIN, CONNECTICUT.

FLOOR OR CEILING PLATE.

1,185,580.

Specification of Letters Patent. Patented May 30, 1916.

Application filed December 4, 1915. Serial No. 64,991.

To all whom it may concern:

Be it known that I, ALLAN J. BEATON, a citizen of the United States, residing at New Britain, in the county of Hartford and State of Connecticut, have invented 5 certain new and useful Improvements in Floor or Ceiling Plates, of which the following is a specification.

This invention relates to what is known 10 as a floor or ceiling plate, the object of the invention being to provide an article of this character which is susceptible of inexpensive and ready manufacture and which possesses maximum strength.

15 In the drawings accompanying and forming part of the present specification I have shown in detail one convenient form of embodiment of the invention which I will fully set forth in the following description. I do not restrict myself to this exact disclosure; I may depart therefrom in several respects within the scope of the invention defined by the claims following said description.

25 Referring to said drawings: Figure 1 is a bottom plan view of a floor or ceiling plate involving the invention. Fig. 2 is an edge view of one of the body members and the various adjuncts carried thereby, looking in the direction of the arrow 2 in Fig. 1. Fig. 3 is a like view of the other body member looking in the direction of the arrow 3 in said Fig. 1. Fig. 4 is a longitudinal section on the line 4—4 of Fig. 1, looking in the direction of the arrow touching the section line. Fig. 5 is a longitudinal section on the line 5—5 of Fig. 1, looking in the direction of the arrow touching said section line.

40 Like characters refer to like parts throughout the several views.

The plate after the usual fashion may and preferably does comprise two body members as 6 and 7 hingedly connected as 45 will hereinafter appear and adapted to abut to present an annular ring inclosing a central opening which receives a pipe or other suitable part. In Fig. 1 the members 6 and 7 are shown in full lines as closed and by 50 dotted lines the body member 6 open, so that the plate can be applied to or removed from a pipe or other device. When the segmental body members 6 and 7 abut to form the ring, the latter as is common will 55 be approximately concavo-convex in cross section.

The member 6 is furnished with a catch-and-hinge member as 8, while the complementary element 7 is equipped with a latch-and-hinge member as 9, each of the members 8 and 9 being bowed and fitting edge-wise against its respective carrying member by which rigidity is obtained. The body member 6 is provided in proximity to the wall of the central opening of the plate 60 with depending lugs or wings 10 and 11 curved longitudinally to conform practically with the curvature of said wall. The longitudinally curved or outwardly bowed intermediate portion of the catch-and-hinge member 8 fits solidly and substantially 65 against the inner surfaces of the wings 8, being united thereto in some suitable manner as by rivets 12. As shown the curvature of the bowed portion 70 of the member 8 is virtually the same as that of the inner surfaces of the wings 10 and 11, so that the curved portion of the member 8 can substantially fit against the wings. The bowed portion of the member 8, therefore, practically hugs the wings so 75 as to preclude possibility of movement of the catch and hinge member. Said member 8 at its rear is doubled or bent on itself to produce the hinge portion 13 which is situated approximately at right angles to the bowed portion of the said member 8. This hinge portion cooperates with a practically similar hinge portion (hereinafter described) on the member 9. It will be noticed that the hinge portion 13 is spaced 80 from the top or upper surface of the segmental body member 6, the complementary hinge portion of the member 9 as will hereinafter appear fitting between the hinge 85 portion 13 and said upper surface. The catch-and-hinge member 8 is provided at its front end with a catch portion 14 which as 90 shown is bent from said member 8 and is practically at right angles to the bowed portion of said member. This catch portion 14 fits flatwise against the substantially flat part of the upper surface of the body member 6. The free or front branch of the catch portion 14 is provided with a projection 15 constituting a catch. The bowed or longitudinally curved intermediate part of the member 9 fits against wings or lugs 16 and 17 on the body member 7, being as 95 shown riveted thereto by rivets 18. The wings 16 and 17 are counterparts of the wings 10 and 11 already described, and the 100 105 110

intermediate part of the latch-and-hinge member 9 is associated with the wings 16 and 17 exactly like the relation between the member 8 and the wings 10 and 11. The member 9 at its rear is shown provided with a hinge portion 18' complementary to the hinge portion 13. This hinge portion 18' is at right angles or approximately so, to the intermediate bowed or body part of the member 9, being spaced from the upper surface of the body member 7. When the segmental members 6 and 7 are closed as shown by full lines in Fig. 1, the hinge portion 13 extends across the butt joint at the rear of said body members and overlies and fits practically flatwise upon the hinge portion 18, the two hinge portions being united in some suitable manner as by the rivet 19. The member 9 is provided at its front end with a latch portion 20 substantially of angular form in plan and the top surface of which is on an inclination. This latch portion 20 is at an angle to the body of the member 9. The operative part of the latch portion 20 is shown as being behind the catch 15 in full lines in Fig. 1 to maintain the closed relation of the plate. To open the plate the two members or sections thereof will be relatively manipulated so as to carry the latch portion 20 free of the catch 15 at which point the part 6 can be moved to the dotted line position to fit around a pipe or the like, and when so fitted the part 6 will be closed and as observed held in a closed relation by the latch portion 20 engaging the catch 15.

In the circular opening of the plate are springs as 21 and 22. The butt of the spring 21 is located as illustrated between the lug 11 and the bowed portion of the catch-and-hinge member 8, being held therebetween in some suitable way as by the rivet 12 which aids in securing said member 8 in position. The spring 22 is positioned at its butt between the wing or lug 17 and the bowed part of the member 9 and is held in position by the rivet 18, one of those which secures said part 9 in place. These springs themselves are common in floor or ceiling plates, and they present a lateral support for the pipe or other object encircled by the plate.

What I claim is:

1. A floor or ceiling plate comprising two segmental body members coöoperative to form a ring, a hinge-and-catch member connected to and fitting edgewise against one of the body members, and a hinge-and-latch member connected to and fitting edgewise against the other body member, the hinge portions of the catch-and-hinge and latch-and-hinge members being pivoted to each other, and the latch and catch portions coöperating to maintain the members in closed position.

2. A floor or ceiling plate comprising two segmental body members each having a projecting winged portion, a hinge-and-catch member fitting edgewise against one of the body members and connected with the winged portion thereof, and a hinge-and-latch member fitting edgewise against the other body member and connected with the winged portion thereof, the hinge portions of the catch-and-hinge and the latch-and-hinge members being pivoted to each other and the latch and catch portions coöperating to hold said body members in closed relation. 70

3. A floor or ceiling plate comprising two segmental body members adapted to approximately abut at their ends when the plate is closed, each member having a winged portion conforming substantially to the curvature of the inner side thereof, a hinge-and-catch portion fitting edgewise against one of the body members and bowed to conform to and connected with the winged portion thereof, and a hinge-and-latch member fitting edgewise against the other body member and conforming to and connected with the winged portion thereof, the hinge portions of the catch-and-hinge and latch-and-hinge members being pivoted to each other, and the latch and catch portions coöperating to hold said body members in closed position. 80

4. A floor or ceiling plate comprising two segmental body members adapted approximately to abut at their ends when the plate is closed, each member having projecting wings longitudinally curved, a hinge-and-catch member fitted edgewise against one of the body members and longitudinally curved between its ends to conform to and connected with the wings thereof, and a hinge-and-latch member fitted edgewise against the other body member and longitudinally bowed between its ends to fit against the wings of said body member, the hinge portions of the catch-and-hinge and latch-and-hinge members being pivoted to each other, and the latch and catch portions coöperating to hold said body members in closed position. 100

5. A floor or ceiling plate comprising two segmental body members adapted approximately to abut at their ends when the plate is closed, each member having projecting wings longitudinally curved, a hinge-and-catch member fitted edgewise against one of the body members and longitudinally curved between its ends to conform to and connected with the wings thereof, a hinge-and-latch member fitted edgewise against the other body member and longitudinally bowed between its ends to fit against the wings of said body member, the hinge portions of the catch-and-hinge and latch-and-hinge members being pivoted to each other, and the latch and catch portions coöperat- 110

ing to hold said body members in closed position, and springs, one spring being fitted between the bowed portion of said latch-and-hinge member and a coöperating wing, and the other spring being disposed between the catch-and-hinge member and a coöperating wing.

6. A floor or ceiling plate comprising two segmental body members substantially abutting against their ends when the plate is closed, a member connected to and fitting edgewise against one of the body members and bowed between its ends to conform to the curvature of the body member to which it is connected and having a hinge portion at one end and a catch portion at the other,

located approximately at right angles to the bowed portion, a member connected to and fitting edgewise against the other body member and bowed between its ends and 20 having a hinge portion approximately at right angles to the bowed portion at one end and a latch portion at the other end, the two hinge portions being pivoted to each other and the latch and catch portions co- 25 operating to hold said body members closed.

In testimony whereof I affix my signature in presence of two witnesses.

ALLAN J. BEATON.
